UNITED STATES PATENT OFFICE.

JAMES A. GIESE, OF CHICAGO, ILLINOIS, ASSIGNOR TO THE ADAMS & WESTLAKE COMPANY, A CORPORATION OF ILLINOIS.

PADLOCK.

1,034,998.

Specification of Letters Patent.

Patented Aug. 6, 1912.

Application filed December 16, 1911. Serial No. 666,238.

To all whom it may concern:

Be it known that I, JAMES A. GIESE, a citizen of the United States, and resident of Chicago, county of Cook, and State of Illinois, have invented certain new and useful Improvements in Padlocks, of which the following is a specification, and which are illustrated in the accompanying drawings, forming a part thereof.

10 The invention relates to padlocks and has for its object to provide a lock of this character which shall be more reliable in operation and of improved construction and which shall permit of an increased number 15 of deviations in the form of key required to open the same.

The invention is exemplified in the structure to be hereinafter described and which is illustrated in the accompanying drawings, 20 in which—

Figure 1 is a plan view of a padlock embodying the features of improvement provided by the invention, the front wall of the lock casing being removed to show the 25 internal construction; Fig. 2 is similar to Fig. 1 but shows the parts of the lock in a different position; Fig. 3 is also similar to Fig. 1 but illustrates the lock with some of the operative parts of the mechanism re- 30 moved; Figs. 4 and 5 are sectional views taken on the lines 4—4 and 5—5 respectively of Fig. 1; Figs. 6 and 7 are perspective views showing details of the operative mechanism of the padlock.

35 The invention is illustrated as being embodied in a padlock having a chambered casing 10 of usual shape and a shackle 11 which is pivoted to the walls of the casing at 12. The point of the shackle 11 is adapt- 40 ed to enter the chamber of the casing through an opening 14 in an end wall of the same and has the usual bolt receiving aperture 13 adjacent its end.

In carrying out the invention a jointed 45 bolt is preferably provided for securing the end of the shackle within the chamber of the casing 10. As shown, this bolt comprises a pivoted member 15 and a longitudinally slid able member 16 both housed 50 within the chamber of the casing 10. The pivoted member 15 swings upon a stationary pivot 17 and is provided with a hook 18 upon one of its ends, which hook enters the aperture 13 in the end of the shackle

when the lock is closed. The pivoted member 15 and sliding member 16 are operatively connected whereby the sliding of the member 16 turns the member 15 upon its pivot. As shown, this connection takes the form of a pin 19 which projects from a side 55 face of the member 16 and moves in a slotted opening 20 in the member 15. The bolt members are normally retained in position for securing the end of the shackle by means of a spring 21. This spring is preferably 60 coiled about the pivot 17 and has its opposite ends reacting respectively upon a stationary stop 22 and upon the pin 19.

The sliding bolt member 16 is provided with a shoulder as 23, (Figs. 3 and 7) for 70 engagement by the bit 24 of a key 25 for moving the bolt members against the effort of the spring 21, to open the lock. Tumblers, as 26, which may be of any well known construction and of which any usual number may be used, are provided to prevent the movement of the bolt members except by the use of a properly formed key. As shown, the tumblers are provided with slotted recesses 27 adapted to receive a stud 75 28 on the bolt member 16 when brought into register with said stud by the bit of the key in the usual way. Provision is also made for securing the bolt members 15, 16 in open position, when the shackle 11 has 80 been released. As shown, a bridge plate 29 is provided for this purpose. This bridge plate swings upon a stationary pivot 30 and normally bears against the end of the shackle 11 to swing the shackle upon the 85 pivot 12 when the bolt members are released. To this end, the bridge plate 29 is moved in one direction by a spring, as 31. This spring may take the form usually employed for the operation of lock tumblers, and as 90 shown has one end fixed in an end of the bridge plate 29 adjacent the pivot 30, as at 32, the other end of the spring being adapted to react against a fixed part of the lock casing, as the shoulder 33, to raise the 95 bridge plate.

The swinging of the bridge plate 29 about the pivot 30 is preferably limited in each direction, as by providing the free end of the same with a slotted opening 34 through 100 which the pivot 17 extends. A shoulder 35 formed on the bridge plate 29 serves as a stop for holding the bolt members 15, 16 in

open position when the bridge plate is raised. For this purpose the shoulder 35 coöperates with a stud 36 carried by the bolt member 16. The bridge plate 29 may also 5 serve to prevent the opening of the lock except by a properly formed key, thereby adding to the security of the lock. As shown, the lower edge of the bridge plate is extended toward the key to such an extent that it 10 will only be cleared by the bit 24 during the turning of the key to open the lock, when the bit be recessed, as indicated at 37.

In the operation of the lock the key 25 is inserted and rotated in the usual way. The 15 bit 24, being properly recessed to clear the bridge plate 29 and to raise the tumblers 26 in proper amounts to bring their recesses, as 27, into line with the stud 28 on the bolt member 16, the bolt members 15, 16, are 20 moved against the effort of the spring 21 by the engagement of the bit 24 with the shoulder 23. Upon the withdrawal of the hooked end 18 of the bolt member 15 from the aperture 13 in the point of the shackle, the end 25 of the shackle is thrown out of the chamber of the lock casing by the raising of the bridge plate through the pressure exerted by the spring 31. This raising of the bridge plate 29 brings the shoulder 35 behind the 30 stud 36, thus holding the bolt members 15, 16 in open position. In closing the lock, the bridge plate 29 is moved downwardly to release the shoulder 35 from the stud 36 by the engagement of the point of the shackle, 35 with the upper edge of the bridge plate, thereby permitting the spring 21 to throw the hooked end 18 of the bolt member 15 into the bolt receiving aperture 13 of the shackle.

The construction provides a lock of reliable 40 operation and as the bridge plate 29 prevents the opening of the lock except by a properly formed key, it, in effect, serves as an additional tumbler and therefore adds to

the security with which the parts of the lock are held in closed position.

I claim as my invention

1. In a padlock, in combination, a shackle, a sliding member having a lateral stud, an oscillatable plate having a shoulder engageable with the stud when the sliding member is retracted, and a spring urging the plate into position for engagement with the stud, the plate extending into the path of the shackle end and being movable in opposition to its spring by the closing of the shackle.

2. In a padlock, in combination, a shackle, a jointed bolt comprising operatively connected pivoted and sliding members, the pivoted bolt member being engageable with the shackle and the sliding member having a shoulder for engagement by the key, a tumbler coöperating with the sliding bolt member, a stud on the sliding bolt member, a bridge plate having a shoulder movable into the path of the said stud on the opening of the lock and a spring urging the bridge plate against the end of the shackle.

3. In a padlock, in combination, a casing, a shackle pivoted to the casing its free end being apertured and being arranged to enter the casing, a spring advanced latch pivoted to the casing and engageable with the aperture of the shackle, a key controlled sliding member attached to the latch and having a lug, a plate pivoted to the casing and bearing against the end of the shackle when such end is within the casing, and having a shoulder for engagement by the lug when the sliding plate is in retracted position, and a spring urging the pivoted plate toward the shackle end.

JAMES A. GIESE.
